UNITED STATES PATENT OFFICE.

HARRY FRIELAND, OF NEWARK, NEW JERSEY, ASSIGNOR TO VOGUE MANUFACTURING CO., OF NEWARK, NEW JERSEY, A FIRM.

DESIGN FOR A BRASSIÈRE.

56,592.

Specification for Design.

Patented Nov. 16, 1920.

Application filed February 17, 1920. Serial No. 359,348. Term of patent 3½ years.

To all whom it may concern:

Be it known that I, HARRY FRIELAND, a citizen of the United States, and a resident of Newark, in the county of Essex and State of New Jersey, United States of America, have invented a new, original, and ornamental Design for a Brassière.

Reference is to be had to the accompanying drawing which shows a perspective view of a brassière embodying my new design.

I claim:

The ornamental design for a brassière, as shown.

HARRY FRIELAND.
